VENTILATED REFLECTOR HOUSING FOR MOTOR VEHICLE LAMP

CROSS-REFERENCE TO RELATED APPLICATIONS

This application claims priority to French Application No. 0957072 filed Oct. 9, 2009, which application is incorporated herein by reference and made a part hereof.

BACKGROUND OF THE INVENTION

1. Field of the Invention

The invention relates in particular to a motor vehicle lighting and/or signalling device.

2. Description of the Related Art

Due to U.S. Pat. No. 5,609,407, a light device is known comprising a housing provided with a ventilation hole communicating with the inside of this housing. In one of the examples described in this patent, the ventilation hole faces a plate forming a reflector. In another example in this patent, the ventilation hole opens onto a reflecting surface formed by a coating on the inside of the housing, this hole then being visible when the front of the device is viewed.

EP 579 555 and its corresponding U.S. Pat. No. 5,457,616 disclose ventilation means.

What is needed, therefore, is a system and method for improving the aesthetics of the device without increasing its complexity.

SUMMARY OF THE INVENTION

The invention is particularly intended for improving the aesthetics of a light device, but without increasing its complexity.

Therefore, one object of the invention is a motor vehicle lighting and/or signalling device, this device comprising:

a housing comprising a rear opening in which a light source can be fitted to the housing; and
a ventilation hole opening into the rear opening of the housing.

Due to one embodiment of the invention, the ventilation hole can be made invisible from the front of the device, in particular when the latter is viewed along the optical axis, without having recourse to additional parts such as a cover, for example.

With this, it is possible to improve the aesthetics of the device while maintaining effective ventilation inside the housing, this effectiveness being made possible by a circulation of air in close proximity to the light source.

Preferably, the ventilation hole opens radially into the rear opening of the housing.

Thus an observer, viewing the device from the front, would only see the rear opening of the housing, not the ventilation hole. Furthermore, this hole is masked by the light source placed in the rear opening.

Advantageously, the device comprises a ventilating duct forming, at one of its ends, the ventilation hole.

In an example of the invention, the device has an optical axis and the ventilating duct runs obliquely relative to the optical axis, i.e. in a manner not parallel to this optical axis.

Preferably, the ventilating duct runs in a manner substantially perpendicular to the optical axis, which may be advantageous with regard to the dimensions of the device.

In an example of the invention, the ventilating duct is of an inside diameter which increases as the duct runs further away radially from the optical axis.

If desired, the ventilating duct comprises an end receiving a cap, made of plastic for example and arranged to allow air to pass through the ventilating duct.

Advantageously, the cap defines an air circulation channel between the outside and the ventilating duct.

If necessary, the ventilation hole is made in one piece with the housing.

Advantageously, the ventilating duct is made in one piece with the housing.

10 In an example of the invention, the housing comprises a rear neck, which is in particular substantially cylindrical, adjacent to the rear opening receiving the light source and the ventilation hole is formed at least partially on this rear neck.

By way of an example, the light source comprises a bulb fitted to a bulb holder, which is fitted in the rear opening of the housing.

The ventilation hole is preferably directly opposite the bulb holder.

20 If necessary, a gasket is placed between the bulb holder and the housing.

In an example of the invention, the device comprises a reflector formed in particular by a reflecting coating deposited on an internal surface of the housing.

The ventilation hole is preferably distant from the reflector.

By way of an example, the housing is of a shape which is substantially generated by rotation about the optical axis.

The device can form, for example, a fog lamp or a DRL ('Daytime Running Light').

30 The invention may be understood better when the detailed description below of a non-limiting example of the invention is read and when the attached drawing is examined, in which:

BRIEF DESCRIPTION OF THE ACCOMPANYING DRAWINGS

35 FIG. 1 shows, schematically and partially, in cross section, a device according to an example of the invention.

DETAILED DESCRIPTION OF THE PREFERRED EMBODIMENTS

There has been shown in FIG. 1 a motor vehicle lighting and/or signalling device 1, this device 1 having an optical axis X and comprising:

45 a housing 2, made of plastic for example, arranged to receive a light source 3, a filament lamp for example;

a lens 8 arranged to close the housing 2, this lens 8 comprising an assembly part 4 arranged to co-operate with an assembly part 5, a flange for example, of the housing 2;

50 a rear opening 9 of the housing 2 in which the light source 3 is fitted to the housing; and

a ventilation hole 10 opening into the rear opening 9 of the housing 2.

The ventilation hole 10 opens radially into the said rear opening 9 of the housing 2.

55 The device 1 comprises a ventilating duct 11 forming, at one of its ends 12, the ventilation hole 10.

The ventilating duct 11 runs obliquely relative to the optical axis X, i.e. in a manner not parallel to this optical axis.

60 In the example described, the ventilating duct 11 runs in a manner substantially perpendicular to the optical axis X.

The ventilating duct 11 is of an inside diameter D which increases as the duct runs further away radially from the optical axis X.

65 The ventilating duct 11 comprises an end 13 receiving a cap 14 arranged to allow air to pass through the ventilating duct 11.

The cap **14** defines an air circulation channel **15** between the outside and the ventilating duct **11**.

The ventilation hole **10** is made in one piece with the housing **2**.

The ventilating duct **11** is made in one piece with the housing **2**.

The housing **2** comprises a rear neck **20**, which is in particular substantially cylindrical, adjacent to the rear opening **9** receiving the light source **3** and the ventilation hole **10** is formed on this rear neck **20**.

The light source **3** comprises a bulb **21** fitted to a bulb holder **22**, which is fitted in the rear opening **9** of the housing **2**.

The ventilation hole **10** directly faces the bulb holder **22**.

A gasket **23** is placed between the bulb holder **22** and the housing **2**.

The housing **2** comprises a reflector **25** formed by a reflecting coating deposited on an internal surface **26** of the housing **2**.

The ventilation hole **10** is distant from the reflector **25**.

The housing **2** is of a shape which is substantially generated by rotation about the optical axis X.

In the example, the device forms a fog lamp or a DRL (Daytime Running Light).

While the forms of apparatus herein described constitute preferred embodiments of this invention, it is to be understood that the invention is not limited to these precise forms of apparatus, and that changes may be made therein without departing from the scope of the invention which is defined in the appended claims.

What is claimed is:

1. A motor vehicle device having an optical axis, this device comprising:

a housing adapted to be mounted on a motor vehicle and comprising a rear opening in which a light source can be fitted to the housing;

a lens attached to said housing generally opposite said rear opening to close said housing;

a light source holder for mounting in said rear opening, said light source holder holding said light source;

a ventilation hole opening into said rear opening of said housing, said ventilation hole being generally opposite or adjacent said light source holder when said light source is mounted in said housing;

said ventilation hole not being visible to an observer viewing said device along the optical axis of said device after it is mounted to the motor vehicle;

said device emitting light through said lens and away from the motor vehicle to perform at least one of lighting or signaling outside the motor vehicle, when said device is mounted on the motor vehicle;

wherein said device forms a fog lamp or a DRL.

2. The motor vehicle device according to claim 1, wherein said ventilation hole is made in one piece with said housing.

3. The motor vehicle device according to claim 1, wherein said housing comprises a rear neck, which is substantially cylindrical, adjacent to said rear opening receiving said light source and in that said ventilation hole is formed at least partially on said rear neck.

4. The motor vehicle device according to claim 1, wherein said housing is of a shape which is substantially generated by rotation about the optical axis.

5. The motor vehicle device according to claim 1, wherein said device is a signaling device.

6. The motor vehicle device according to claim 1, wherein said device is a both a lighting and a signaling device.

7. The motor vehicle device according to claim 1, wherein said device is a lighting device.

8. The motor vehicle device according to claim 1, wherein it comprises a reflector formed by a reflecting coating deposited on an internal surface of said housing.

9. The motor vehicle device according to claim 8, wherein said ventilation hole is distant from said reflector.

10. The motor vehicle device according to claim 1, wherein it comprises a ventilating duct forming, at one of its ends, said ventilation hole.

11. The motor vehicle device according to claim 10, wherein said ventilating duct runs in a manner substantially perpendicular to the optical axis.

12. The motor vehicle device according to claim 10, wherein said housing comprises a rear neck, which is substantially cylindrical, adjacent to said rear opening receiving said light source and in that said ventilation hole is formed at least partially on said rear neck.

13. The motor vehicle device according to claim 10, wherein it comprises a reflector formed by a reflecting coating deposited on an internal surface of said housing.

14. The motor vehicle device according to claim 1, wherein said ventilation hole opens radially into said rear opening of said housing.

15. The motor vehicle device according to claim 14, wherein said ventilation hole is made in one piece with said housing.

16. The motor vehicle device according to claim 14, wherein said housing comprises a rear neck, which is substantially cylindrical, adjacent to said rear opening receiving said light source and in that said ventilation hole is formed at least partially on said rear neck.

17. The motor vehicle device according to claim 14, wherein it comprises a reflector formed by a reflecting coating deposited on an internal surface of said housing.

18. The motor vehicle device according to claim 17, wherein said ventilation hole is distant from the reflector.

19. A motor vehicle device, this device comprising:

a housing adapted to be mounted on a motor vehicle and comprising a rear opening in which a light source can be fitted to said housing,

a lens attached to said housing generally opposite said rear opening to close said housing;

a light source holder for mounting in said rear opening, said light source holder holding said light source;

a ventilation hole opening into said rear opening of said housing, said ventilation hole being generally opposite or adjacent said light source holder when said light source is mounted in said housing;

said ventilation hole not being visible to an observer viewing said device along the optical axis of said device after it is mounted to the motor vehicle;

said device emitting light through said lens and away from the motor vehicle to perform at least one of lighting or signaling outside the motor vehicle, when said device is mounted on the motor vehicle; and

a ventilating duct forming, at one of its ends, said ventilation hole, said ventilating duct running in a manner substantially perpendicular to an optical axis;

wherein said device forms a fog lamp or a DRL.

20. The motor vehicle device according to claim 19, wherein said ventilation hole is made in one piece with said housing.

21. The motor vehicle device according to claim 19, wherein said housing comprises a rear neck, which is substantially cylindrical, adjacent to said rear opening receiving

said light source and in that said ventilation hole is formed at least partially on said rear neck.

22. The motor vehicle device according to claim 19, wherein it comprises a reflector formed by a reflecting coating deposited on an internal surface of said housing. 5

23. The motor vehicle device according to claim 19, wherein said housing is of a shape which is substantially generated by rotation about the optical axis.

24. The motor vehicle device according to claim 19, wherein said device is a signaling device. 10

25. The motor vehicle device according to claim 19, wherein said device is both a lighting and a signaling device.

26. The motor vehicle device according to claim 19, wherein said device is a lighting device.
